UNITED STATES PATENT OFFICE.

EZRA R. GUDEMAN, OF BALTIMORE, MARYLAND, AND GEORGE JOSEPH MACK, OF BROOKLYN, NEW YORK, ASSIGNORS TO U. S. INDUSTRIAL ALCOHOL CO., A CORPORATION OF WEST VIRGINIA.

VALVE-OPERATING DEVICE FOR TANK CARS.

Application filed February 12, 1921. Serial No. 444,554.

To all whom it may concern:

Be it known that we, EZRA R. GUDEMAN, a citizen of the United States, and a resident of Baltimore, Maryland, and GEORGE 5 JOSEPH MACK, a citizen of the United States, residing at Brooklyn, in the county of Kings and State of New York, have invented a certain new and useful Improvement in Valve-Operating Devices for Tank Cars, of 10 which the following is a specification.

Our invention relates particularly to a device adapted to operate valves in tank cars but is applicable also to the operation of valves in many other constructions.

15 The object of our invention is to provide an operating mechanism for valves by means of which the valves may be securely locked in position when closed but which are so arranged that they may be readily opened 20 when required.

A further object is to locate the valve controlling mechanism in the interior of the tank car so that the valve cannot be opened except when the cover of the tank car has 25 been removed.

Still another object is to provide a removable locking element in the tank car which is supported from the wall of the same so that it is ready at all times to be moved into 30 place for locking the valve when the cover of the tank car is open.

From the following description further objects of our invention will be apparent.

Our invention may be embodied in many 35 different forms of apparatus but by way of example we have shown only certain forms of the same in the accompanying drawings in which—

Figure 1 is a side elevation of one form 40 of our invention shown on the interior of a tank car.

Figure 1^a is a vertical section of a valve adapted to be operated by our operating mechanism.

45 Figure 2 is a plan view of a portion of apparatus shown in Figures 1 and 1^a, and

Figure 3 is a side elevation of a modified form of our invention.

In the drawings, referring first to Figures 50 1, 1^a and 2, we have shown a tank car 1 having a dome 2 provided with a dome plate 3 having a screw-threaded flange 4 to receive a screw-threaded flange 5 on a removable dome cover 6. The dome plate 3 is

riveted to the dome 2 by means of rivets 7. 55 Cooperating with the head of one of the rivets 7 in the interior of the tank car, there is a pipe coupling 8 which is screw-threaded upon the end of a pipe 9 having a supporting ring 10 connected by a chain 11 to a 60 bracket 12 projecting from the side of the dome 2. The lower end of the pipe 9 is arranged to fit over the upper screw-threaded end of a valve rod 13, which projects through a hole 14 in the end of the bracket 65 12. The extreme lower end of the pipe 9 contacts with a nut 15 on the rod 13, which nut overlies a washer 16 located above a handle 17 having an inclined cylindrical elevating and strengthening portion 18 fitting 70 over the end of the bracket 12. Beneath the bracket 12 the rod 13 carries a coil spring 19, the lower end of which is supported by a sleeve 20 secured on the rod 13. The rod 13 furthermore at its extreme lower 75 end carries a plunger valve 21 fitting within a tapering outlet opening 22 provided in an outlet plate 23 riveted to the tank car 1.

The other form of our invention shown 80 in Figure 3 is constructed the same as the form of the invention shown in Figures 1, 1^a and 2, except that in the form shown in Figure 3 there is provided a pipe 24 which is supported by means of a hinge 25 secured to the pipe and to the dome 2 by suitable 85 rivets, and except that this pipe 24 has screw-threaded upon its lower end a pipe coupling 26 adapted to contact with the nut 15.

In the operation of our invention as shown 90 in Figures 1, 1^a and 2, when the cover 6 of the dome 2 has been secured in place, it is not possible to disturb the valve operating mechanism as the latter is entirely enclosed within the tank car. When, however, the cover 6 has been removed for discharging 95 the contents of the car, the pipe coupling 8 is unscrewed until it is released from the rivet head at the top of the car and the pipe 9 is then removed from over the end of the valve rod 13 and is held suspended on the 100 end of the chain 11 so that it cannot drop to the bottom of the car. The hand lever 17 can be rotated to lift the rod 13 now in opposition to the force of the spring 19 so as to remove the valve 21 from the opening 22. 105 The contents of the tank car will then flow out until the car is emptied. In order to fill the tank car the valve 21 is allowed to be

returned to its seat by the force of the coil spring 19 after the handle 17 has been turned into its original position. The pipe 9 is placed over the upper end of the rod 13 and the pipe coupling 8 is screwed into place. After the car is filled the cover 6 is screwed into place thus closing the car ready for transport.

The other form of our invention shown in Figure 3 operates in the same manner except in the following respects: In this instance, in order to release the valve, the pipe coupling 26 is unscrewed and the pipe 24 is moved upwardly on the hinge 25 so as to be out of the way of the valve rod 13 when moved upwardly by the handle 17. While the car is being emptied the pipe 24 is supported by the hinge 25 so that it cannot drop to the bottom of the car.

By means of this mechanism it will be seen that the draw-off valve of the tank car cannot be opened from the exterior without the previous opening of the dome cover and inasmuch as this dome cover may be locked in place with any suitable lock, as for example the form of lock shown in the co-pending application of George Joseph Mack relating to closures, executed on the 6th day of January 1921, it will be understood that the locking of the cover also results in the locking of the draw-off valve. When, however, the car is to be emptied the operating mechanism for the valve may be readily reached so that the pipe over the upper end of the valve rod may be removed to permit the valve rod 13 to be moved so as to open the draw-off valve. Furthermore, when the valve is to be closed the pipe referred to is always ready so that it may be introduced over the end of the valve rod and secured in place to lock the valve closed.

Our invention has been described in detail above but any changes may be made within the scope of our invention without departing from the spirit of the same.

We claim:

1. A valve operating mechanism for tank cars and the like comprising a valve opening rod, and an adjustable screw-threaded pipe coupling adapted to be inserted in the path of movement of the rod to prevent positively any upward motion thereof when the valve is closed, said coupling being operable from the dome of the car.

2. A valve operating mechanism for tank cars and the like comprising a valve opening rod, an adjustable screw-threaded pipe coupling attachable to the dome of the car and adapted to be inserted in the path of movement of the rod to prevent positively any upward motion thereof when the valve is closed.

3. The combination of a tank car, a valve operating mechanism comprising a valve opening rod and a removable adjustable stop

adapted to be inserted in the path of movement of the same to prevent the opening of the valve, said stop being supported from the tank car, and said tank car having a rivet which cooperates with the end of the stop when the valve is locked in position.

4. The combination of a tank car, a valve operating mechanism comprising a valve opening rod and a removable adjustable stop comprising a screw-threaded pipe coupling, said stop being supported from the tank car, and said tank car having a rivet which cooperates with the end of the pipe coupling when the valve is locked in position.

5. The combination of a tank car, a valve operating mechanism comprising a valve opening rod and a removable adjustable stop adapted to be inserted in the path of movement of the same to prevent the opening of the valve, said stop being supported from the tank car when in use, and said tank car also having a flexible supporting means for the stop when the valve is in open position.

6. The combination of a tank car, a valve operating mechanism comprising a valve opening rod and a removable adjustable stop comprising a screw-threaded pipe coupling, said stop being supported from the tank car, and said tank car also having a flexible supporting means for the stop when the valve is in open position.

7. The combination of a tank car, a valve operating mechanism comprising a valve opening rod and a removable adjustable stop adapted to be inserted in the path of movement of the same to prevent the opening of the valve, said stop being supported from the tank car in a conveniently accessible position, said tank car having a bracket supporting the valve opening rod, and said valve opening rod having an operating handle and an inclined ring enclosing the outer end of the bracket.

8. The combination of a tank car, a valve operating mechanism comprising a valve opening rod and a removable adjustable stop comprising a screw-threaded pipe coupling, said stop being supported from the tank car, said tank car having a bracket supporting the valve opening rod and said valve opening rod having an operating handle and an inclined ring enclosing the outer end of the bracket.

9. A valve operating mechanism for tank cars and the like comprising a valve opening rod, and an adjustable screw-threaded pipe coupling flexibly suspended from the dome of the car and adapted to be inserted in the path of movement of the rod to prevent positively any upward motion thereof when the valve is closed.

10. The combination of a tank car, having a dome cover and located near the same, a valve operating mechanism comprising a

valve opening rod and a removable adjustable stop adapted to be inserted in the path of movement of the same to prevent the opening of the valve, said stop being supported from the tank car, and said tank car having a rivet which cooperates with the end of the stop when the valve is locked in position.

11. The combination of a tank car, having a dome cover and located near the same, a valve operating mechanism comprising a valve opening rod and a removable adjustable stop carrying a screw-threaded pipe coupling, said stop being supported from the tank car, and said tank car having a rivet which cooperates with the end of the pipe coupling when the valve is locked in position.

12. The combination of a tank car, having a dome cover and located near the same, a valve operating mechanism comprising a valve opening rod and a removable adjustable stop adapted to be inserted in the path of movement of the same to prevent the opening of the valve, said stop being supported from the tank car and said tank car also having a flexible supporting means for the stop when the valve is in open position.

13. The combination of a tank car, having a dome cover and located near the same, a valve operating mechanism comprising a valve opening rod and a removable adjustable stop comprising a screw-threaded pipe

coupling, said stop being supported from the tank car and said tank car also having a flexible supporting means for the stop when the valve is in open position.

14. The combination of a tank car, having a dome cover and located near the same, a valve operating mechanism comprising a valve opening rod and a removable adjustable stop adapted to be inserted in the path of movement of the same to prevent the opening of the valve, said stop being supported from the tank car and said tank car having a bracket supporting the valve opening rod which valve opening rod has an operating handle and an inclined ring enclosing the end of the bracket.

15. The combination of a tank car, having a dome cover and located near the same, a valve operating mechanism comprising a valve opening rod and a removable adjustable stop carrying a screw-threaded pipe coupling, said stop being supported from the tank car and said tank car having a bracket supporting the valve opening rod, which valve opening rod has an operating handle and an inclined ring enclosing the end of the bracket.

In testimony that we claim the foregoing, we have hereunto set our hands this 26th day of January, 1921, and 6th day of January, 1921, respectively.

EZRA R. GUDEMAN.
GEORGE JOSEPH MACK.
